UNITED STATES PATENT OFFICE

HARRY W. LAWRENCE, OF DENVER, COLORADO

DESIGN FOR A LIGHT SCREEN

Application filed April 4, 1931. Serial No. 39,374. Term of patent 7 years.

To all whom it may concern:

Be it known that I, HARRY W. LAWRENCE, a citizen of the United States, residing at Denver, in the county of Denver and State of Colorado, have invented a new, original, and ornamental Design for Light Screens, of which the following is a specification, reference being had to the accompanying drawing, forming part hereof.

The drawing illustrates a perspective view of my new design.

The screen is in the form of a relatively thin flat plate (or sheet) of material. The jewels arranged within the star outline, as shown, are set in said plate so as to project from the front face thereof.

I claim:

The ornamental design for a light screen as shown and described.

HARRY W. LAWRENCE.
